PNEUMATIC TIRE

James F. Newman, St. Clair Shores, Mich., assignor to
Uniroyal, Inc., New York, N.Y.

Filed Sept. 3, 1970, Ser. No. 24,819

Term of patent 14 years

Int. Cl. D12—15

U.S. Cl. D90—20

FIG. 1 is a perspective view of a pneumatic tire showing my new design, it being understood that the shaded tread and buttress portions continue throughout the circumference of the tire, and that the buttress pattern is the same on both sides of the tire;

FIG. 2 is an enlarged, fragmentary plan view of the tread of FIG. 1;

FIG. 3 is an enlarged, fragmentary plan view of the buttress of FIG. 1;

FIG. 4 is a fragmentary sectional view of the tread, taken substantially on the plane indicated by line 4-4 of FIG. 2; and

FIG. 5 is a fragmentary sectional view of the buttress, taken substantially on the plane indicated by line 5-5 of FIG. 3.

The characteristic feature of my design resides in the tread and buttress pattern extending from one sidewall of the tire to the other.

I claim:

The ornamental design for a pneumatic tire, substantially as shown and described.
